UNITED STATES PATENT OFFICE.

GEORGE W. BULLEY, OF AKRON, OHIO, ASSIGNOR TO THE MILLER RUBBER COMPANY, OF AKRON, OHIO, A CORPORATION OF OHIO.

SOUND-AMPLIFYING HORN.

Original application filed February 8, 1926, Serial No. 26,869. Divided and this application filed June 19, 1926. Serial No. 117,163.

My present invention relates to improvements in sound amplifying horns such as are used for radio loud speakers and kindred purposes, and concerns particularly horns 5 which are made of hard vulcanized rubber, though not limited in all its aspects to this particular material.

In the manufacture of such horns it has been customary to form a hollow biscuit 10 of unvulcanized sheet rubber of approximately the shape of the desired horn and place this in a mold having an internal cavity of the desired shape, and subject it to a vulcanizing heat while at the same time 15 expanded by fluid pressure supplied by the volatilization of a blowing agent inserted within the biscuit, the pressure of the fluid from the blowing agent forcing the material against the walls of the mold, where it becomes vulcanized to the consistency of hard 20 rubber.

In order to confine the gas in such an article during manufacture, it is necessary to provide a blow-over at each end thereof, or 25 in other words, a closed end which must be removed after the molding of the article.

It is also necessary that the neck of the horn shall be provided with means for connection to the loud speaking device. The 30 commercial types of loud speaking devices differ materially in size, which requires that the standard types and sizes of horn shall be manufactured each with large variations in the neck connections, which neck connections must be firmly attached to the horns so 35 that no air leaks take place at the point of connection to the loud speaking device.

The present invention aims to provide a method and means whereby a metal ferrule 40 may be rigidly attached to the neck of the horn during the manufacture in such a manner as to support the blow-over and retain the fluid pressure, and in which such blow-over may be readily bored out to secure the 45 necessary air passage.

The invention aims further to provide means whereby a horn of the standard type or size may be produced with means whereby it may be readily adapted for connection with any one of the various sizes of standard 50 loud speakers, thereby greatly reducing the amount of stock necessary to be produced and carried on hand.

With these and other objects in view, the

invention includes the novel article herein- 55 after described, and particularly defined in the appended claims.

In order that my invention may be better understood, reference is made to the accompanying drawing, in which:— 60

Figure 1 is a sectional view through a horn member as it appears upon the completion of the vulcanization.

Figs. 2 and 2^a are sectional views illustrating supplemental and interchangeable 65 nipples for application thereto, and

Fig. 3 is a sectional view illustrating the boring out of the blow-over.

It may be stated at this point that horns of a large size are customarily made in two 70 sections for convenience in manufacture, due to complication in shape, these sections being known respectively as the goose-neck and the bell, but for small horns the goose-neck, or a part equivalent thereto, would suffice, and for convenience of illustration I 75 have shown in the present drawing only the goose-neck part, which in the present drawing is numbered 1. While the biscuit is in its plastic and unvulcanized condition, 80 a metal ferrule 2 is applied to the small end thereof, which metal ferrule has a closed end 2^a and is provided with an inwardly swaged portion or portions for interlocking 85 with the rubber neck for rigidly holding the ferrule in place, which interlock is preferably formed in the shape of an inwardly swaged portion 2^b which forms an internal annular rib and corresponding external annular groove. The closed end wall 2^a cooperates 90 in supporting the blow-over forming material, which is indicated at 1^a.

Preferably the closed end is provided with a central indentation α which serves to accurately center the boring bit hereinafter referred to. The vulcanization of the horn in the manner described converts the rubber into hard rubber and causes the ferrule to be rigidly secured in the position shown in Fig. 1. For cooperating with this ferrule 2 100 I provide a plurality of ferrules 3 which have cylindrical parts 3^a, the interior diameter of which accurately fits the external diameter of the ferrule 2, and which are provided with tubular extensions 3^b of sizes 105 corresponding to the various sizes or types of commercial loud speakers. Given an order or demand for horns for attachment to a

loud speaker of a certain type, it is only necessary to pick from stock the requisite number of horns 1 and to assemble on these the ferrules 3 of the proper size. Such ferrule 3 having been slipped onto the ferrule 2, the sheet metal of the wall 3^a which lies over the channel 2^b is spun down into the same either by hand or suitable apparatus, as shown in Fig. 3, interlocking the two firmly together. Thereafter the closed end 2^a and blow-over 1^a are bored out by a suitable drill 4, the extension 3^b serving as a guide for the drill.

Having thus described my invention, what I claim is:

15. 1. A non-metallic sound amplifying horn having a metallic ferrule secured to the small end thereof, and a second ferrule secured to said first named ferrule and provided with 20 a reduced tubular extension.
2. A non-metallic sound amplifying horn having a metallic ferrule encircling the small end thereof and secured thereto, a second metallic ferrule encircling said first named 25 ferrule and secured thereto, said second ferrule having a reduced tubular extension.
3. A non-metallic sound amplifying horn having a metallic ferrule secured to the small end thereof, and provided with an inwardly 30 swaged portion interlocking with the horn

material, and a second ferrule encircling the first named ferrule, and having a part pressed into interlocking engagement with the swaged portion of said first named ferrule, said second ferrule having a tubular extension.

4. A non-metallic sound amplifying horn having a metallic ferrule encircling the small end thereof and interlocked therewith, said ferrule having an inturned annular flange 40 overlying the end of the horn, a second metallic ferrule encircling said first named ferrule in interlocking engagement therewith and having an internal annular shoulder 45 abutting the internal annular flange of the first ferrule and having also a tubular extension.

5. In combination, a sound amplifying horn of hard rubber compound, and a sheet metal ferrule encircling the small end thereof, said metal ferrule having an internal annular rib interlocking with the horn material, and a corresponding external annular channel, and a second sheet metal ferrule encircling the first and having an annular depressed portion engaging said external 50 channel.

In testimony whereof, I affix my signature.

GEORGE W. BULLEY.
